LIQUID EJECTION HEAD

CROSS REFERENCE TO RELATED APPLICATION

The present application claims priority from Japanese Patent Application No. 2018-147776, which was filed on Aug. 6, 2018, the disclosure of which is herein incorporated by reference in its entirety.

BACKGROUND

The following disclosure relates to a liquid ejection head including a plurality of individual passages each having a nozzle.

There is known a liquid ejection head including: second common liquid passages (supply liquid passages) each communicating with inlets of corresponding ones of a plurality of individual passages; and first common liquid passages (return liquid passages) each communicating with outlets of corresponding ones of the plurality of individual passages. Liquid is supplied to the second common liquid passages through their respective one ends. While flowing from the one end to the other end of each of the second common liquid passages, the liquid enters into the inlets of the respective individual passages communicating with the second common liquid passage. The liquid having flowed into each of the individual passages is partly ejected from a nozzle. The remaining portion of the liquid flows into a corresponding one of the first common liquid passages via the outlet of the individual passage. The liquid having flowed into the first common liquid passage flows from one end toward the other end of the first common liquid passage and is collected from the other end of the first common liquid passage.

SUMMARY

In the above-described liquid ejection head, each of the individual passages has one inlet and one outlet. One of the second common liquid passages (the supply liquid passages) is connected to the one inlet, and one of the first common liquid passages (the return liquid passages) is connected to the one outlet. In this configuration, the speed of ink flow easily lowers particularly at corner portions of the individual passage, which may lead to insufficient discharging of air bubbles and insufficient stirring of settling components (components of liquid with a possibility of settling, such as pigments).

Accordingly, an aspect of the disclosure relates to a liquid ejection head capable of reducing lowering of the speed of ink flow in each of individual passages and reducing insufficient discharging of air bubbles and insufficient stirring of settling components.

In one aspect of the disclosure, a liquid ejection head includes: a plurality of individual passages each having a nozzle; a first supply liquid passage communicating with a first inlet of each of the plurality of individual passages; a second supply liquid passage communicating with a second inlet of each of the plurality of individual passages; a first return liquid passage communicating with a first outlet of each of the plurality of individual passages; and a second return liquid passage communicating with a second outlet of each of the plurality of individual passages.

BRIEF DESCRIPTION OF THE DRAWINGS

The objects, features, advantages, and technical and industrial significance of the present disclosure will be better

2

understood by reading the following detailed description of the embodiments, when considered in connection with the accompanying drawings, in which:

- 5 FIG. 1 is a plan view of a printer including heads according to a first embodiment;
 FIG. 2 is a plan view of the head;
 FIG. 3 is an enlarged view of a region III in FIG. 2;
 FIG. 4 is a cross-sectional view taken along line IV-IV in FIG. 3;
 10 FIG. 5 is a block diagram illustrating an electric configuration of the printer;
 FIG. 6 is a cross-sectional view of a head according to a second embodiment, the view corresponding to FIG. 4;
 FIG. 7 is a cross-sectional view of a head according to a 15 third embodiment, the view corresponding to FIG. 4;
 FIG. 8 is a plan view of a head according to a fourth embodiment, the view corresponding to FIG. 4;
 FIG. 9 is a cross-sectional view taken along line IX-IX in FIG. 8; and
 20 FIG. 10 is an enlarged view of a head according to a fifth embodiment, the view corresponding to FIG. 3.

EMBODIMENTS

First Embodiment

Hereinafter, there will be described embodiments by reference to the drawings. First, there will be described, with reference to FIG. 1, an overall configuration of a printer 100 including heads 1 according to a first embodiment.

The printer 100 includes a head unit 1x, a platen 3, a conveying mechanism 4, and a controller 5. The head unit 1x includes the four heads 1.

An upper surface of the platen 3 is capable of supporting a sheet 9.

The conveying mechanism 4 includes two roller pairs 4a, 4b. The platen 3 is interposed between the roller pairs 4a, 4b in a conveying direction. When a conveying motor 4m is driven by the controller 5, the roller pairs 4a, 4b are rotated in a state in which the sheet 9 is nipped by the roller pairs 4a, 4b, whereby the sheet 9 is conveyed in the conveying direction.

The head unit 1x is of a line type and elongated in a widthwise direction of the sheet 9. The line type is a type in which the head unit 1x ejects ink onto the sheet 9 from nozzles 21 (see FIGS. 2-4), with the position of the head unit 1x being fixed. The four heads 1 are arranged in the widthwise direction of the sheet 9 in a staggered configuration.

The controller 5 includes a read-only memory (ROM), a random-access memory (RAM), and an application-specific integrated circuit (ASIC). The ASIC executes various processings, such as a recording processing, according to programs stored in the ROM. In the recording processing, the controller 5 controls the conveying motor 4m and a driver IC 1d of the head 1 (see FIGS. 4 and 5) to record an image on the sheet 9, based on a recording command (containing image data) input from an external device such as a personal computer (PC).

There will be next described a configuration of each of the heads 1 with reference to FIGS. 2-4. Since the heads 1 have the same configuration, the configuration of one of the heads 1 will be described for simplicity.

The head 1 includes a liquid-passage defining plate 11 and an actuator unit 12.

As illustrated in FIG. 4, the liquid-passage defining plate 11 includes nine plates 11a-11i stacked on and bonded to

each other. Each of the plates 11a-11i has through holes constituting liquid passages and openings formed in the liquid-passage defining plate 11.

As illustrated in FIG. 2, passages formed in the liquid-passage defining plate 11 include: a plurality of individual passages 20; a plurality of first supply liquid passages 31a communicating with first inlets 20a1 of the respective individual passages 20; a plurality of second supply liquid passages 31b communicating with second inlets 20a2 of the respective individual passages 20; a plurality of first return liquid passages 32a communicating with first outlets 20b1 of the respective individual passages 20; a plurality of second return liquid passages 32b communicating with second outlets 20b2 of the respective individual passages 20; a supply coupling liquid passage 41 coupling the supply liquid passages 31a, 31b to each other; and a return coupling liquid passage 51 coupling the return liquid passages 32a, 32b to each other.

The supply liquid passages 31a, 31b and the return liquid passages 32a, 32b extend in the same direction that coincides with the widthwise direction of the sheet 9 and may be hereinafter referred to as "extending direction". The supply liquid passages 31a, 31b and the return liquid passages 32a, 32b are arranged in a direction along the conveying direction which may be hereinafter referred to as "arrangement direction". In the present embodiment, the arrangement direction is orthogonal to the extending direction.

As illustrated in FIG. 4, the first supply liquid passages 31a and the respective first return liquid passages 32a overlap each other in the vertical direction (that is orthogonal to each of the extending direction and the arrangement direction and hereinafter may be referred to as "orthogonal direction"). The second supply liquid passages 31b and the respective second return liquid passages 32b overlap each other in the vertical direction. The first supply liquid passages 31a and the second supply liquid passages 31b are located at the same position in the orthogonal direction and located respectively over the first return liquid passages 32a and the second return liquid passages 32b in the vertical direction. In other words, the first supply liquid passages 31a and the second supply liquid passages 31b are located on the other side respectively of the first return liquid passages 32a and the second return liquid passages 32b in the orthogonal direction. The first return liquid passages 32a and the second return liquid passages 32b are located at the same position in the orthogonal direction and located respectively over the first supply liquid passages 31a and the second supply liquid passages 31b in the vertical direction. In other words, first return liquid passages 32a and the second return liquid passages 32b are located on one side respectively of the first supply liquid passages 31a and the second supply liquid passages 31b in the orthogonal direction.

As illustrated in FIG. 2, the first supply liquid passages 31a (the corresponding first return liquid passages 32a) and the second supply liquid passages 31b (the corresponding second return liquid passages 32b) are alternately arranged in the arrangement direction.

Each of the first supply liquid passages 31a communicates with the supply coupling liquid passage 41 via an inlet 31ax formed at a one-side end portion of the first supply liquid passage 31a in the extending direction. Each of the second supply liquid passages 31b communicates with the supply coupling liquid passage 41 via an inlet 31bx formed at a one-side end portion of the second supply liquid passage 31b in the extending direction. A distal end 31at of each of the first supply liquid passages 31a in the extending direction and a distal end 31bt of each of the second supply liquid

passages 31b in the extending direction are closed and located on the other side of corresponding ones of the plurality of individual passages 20 in the extending direction.

- 5 Each of the first return liquid passages 32a communicates with the return coupling liquid passage 51 via an outlet 32ax formed at an other-side end portion of the first return liquid passage 32a in the extending direction. Each of the second return liquid passages 32b communicates with the return coupling liquid passage 51 via an outlet 32bx formed at an other-side end portion of the second return liquid passage 32b in the extending direction. A distal end 32at of each of the first return liquid passages 32a in the extending direction and a distal end 32bt of each of the second return liquid passages 32b in the extending direction are closed and located on one side of corresponding ones of the plurality of individual passages 20 in the extending direction.

Each of the supply coupling liquid passage 41 and the return coupling liquid passage 51 extends in the arrangement direction. The supply coupling liquid passage 41 is located on the one side of the supply liquid passages 31a, 31b and the return liquid passages 32a, 32b in the extending direction. The return coupling liquid passage 51 is located on the other side of the supply liquid passages 31a, 31b and the return liquid passages 32a, 32b in the extending direction. The supply coupling liquid passage 41 and the return coupling liquid passage 51 are arranged so as to be symmetric with respect to a plane extending along the arrangement direction and the orthogonal direction through the center of the liquid-passage defining plate 11 in the extending direction.

The supply coupling liquid passage 41 communicates at its other-side surface in the extending direction with the inlets 31ax of the respective first supply liquid passages 31a and the inlets 31bx of the respective second supply liquid passages 31b. The return coupling liquid passage 51 communicates at its one-side surface in the extending direction with the outlets 32ax of the respective first return liquid passages 32a and the outlets 32bx of the respective second return liquid passages 32b.

The supply coupling liquid passage 41 communicates with a storage chamber 7a of a sub-tank 7 via a supply opening 41x. The supply opening 41x is formed at a one-side end portion of the supply coupling liquid passage 41 in the arrangement direction and is located on one side of coupled portions of the respective supply liquid passages 31a, 31b (the inlets 31ax, 31bx of the respective supply liquid passages 31a, 31b) in the arrangement direction.

The return coupling liquid passage 51 communicates with the storage chamber 7a via a return opening 51x. The return opening 51x is formed at a one-side end portion of the return coupling liquid passage 51 in the arrangement direction and is located on the one side of coupled portions of the respective return liquid passages 32a, 32b (the outlets 32ax, 32bx of the respective return liquid passages 32a, 32b) in the arrangement direction.

The sub-tank 7 is installed in the head 1. The storage chamber 7a communicates with a main tank, not illustrated, for storing the ink and stores the ink supplied from the main tank.

The individual passages 20 are arranged between the supply coupling liquid passage 41 and the return coupling liquid passage 51 in the extending direction. Each of the individual passages 20 is disposed between a corresponding one of the inlets 31ax, 31bx of the respective supply liquid passages 31a, 31b and a corresponding one of the outlets 32ax, 32bx of the respective return liquid passages 32a, 32b.

Each of the individual passages 20 is disposed in the arrangement direction between a corresponding pair of the first supply liquid passage 31a and the first return liquid passage 32a adjacent to each other and a corresponding pair of the second supply liquid passage 31b and the second return liquid passage 32b adjacent to each other.

The individual passages 20 are arranged in five rows, in each of which the individual passages 20 each extending in the extending direction are arranged in the extending direction. The five rows are arranged in the arrangement direction. A pair of the first supply liquid passage 31a and the first return liquid passage 32a and a pair of the second supply liquid passage 31b and the second return liquid passage 32b are formed on opposite sides of each of the rows of the individual passages 20 in the arrangement direction. In the present embodiment, the pair of the first supply liquid passage 31a and the first return liquid passage 32a or the pair of the second supply liquid passage 31b and the second return liquid passage 32b formed between two of the rows of the individual passages 20 which are adjacent to each other in the arrangement direction communicate with the individual passages 20 belonging to the two rows.

As illustrated in FIGS. 3 and 4, each of the individual passages 20 includes: a nozzle 21; a pressure chamber 22 communicating with the nozzle 21; a first inflow passage 23a connecting between the pressure chamber 22 and the first inlets 20a1; a second inflow passage 23b connecting between the pressure chamber 22 and the second inlets 20a2; a first outflow passage 24a connecting between the pressure chamber 22 and the first outlets 20b1; and a second outflow passage 24b connecting between the pressure chamber 22 and the second outlets 20b2. As illustrated in FIG. 3, the pressure chamber 22 is of a rectangular shape extending in the extending direction on the plane extending along the extending direction and the arrangement direction. The pressure chamber 22 has four corner portions c1-c4 and four sides s1-s4. The nozzle 21 is located just under the pressure chamber 22 at a center point O of the pressure chamber 22 on the plane.

Each of the first inflow passage 23a and the first outflow passage 24a extends in the arrangement direction from the side s1 of the pressure chamber 22 which extends in the extending direction. Each of the second inflow passage 23b and the second outflow passage 24b extends in the arrangement direction from the side s2 of the pressure chamber 22 which extends in the extending direction and is opposed to the side s1 in the arrangement direction.

The first inflow passage 23a and the second inflow passage 23b are connected to the respective corner portions c1, c2 of the pressure chamber 22, which are symmetric with respect to the center point O. The first inflow passage 23a and the second inflow passage 23b are arranged so as to be symmetric with respect to the center point O. Likewise, the first inlet 20a1 and the second inlet 20a2 are arranged so as to be symmetric with respect to the center point O.

The first outflow passage 24a and the second outflow passage 24b are connected to the respective corner portions c3, c4 of the pressure chamber 22, which are symmetric with respect to the center point O. The first outflow passage 24a and the second outflow passage 24b are arranged so as to be symmetric with respect to the center point O. Likewise, the first outlets 20b1 and the second outlets 20b2 are arranged so as to be symmetric with respect to the center point O.

The first inflow passage 23a and the second outflow passage 24b are arranged so as to be symmetric with respect to the axis A extending along the extending direction through the center of the pressure chamber 22 in the arrange-

ment direction. The second inflow passage 23b and the first outflow passage 24a are arranged so as to be symmetric with respect to the axis A extending along the extending direction through the center of the pressure chamber 22 in the arrangement direction.

As illustrated in FIG. 4, the first outflow passage 24a and the second outflow passage 24b are located respectively under the first inflow passage 23a and the second inflow passage 23b in the vertical direction. In other words, the first outflow passage 24a and the second outflow passage 24b are located respectively on the one side of the first inflow passage 23a and the second inflow passage 23b in the orthogonal direction.

The nozzle 21 is constituted by through holes formed in the respective plates 11h, 11i. The pressure chamber 22 is constituted by through holes formed in the respective plates 11a-11g. Each of the first inflow passage 23a and the second inflow passage 23b is constituted by a through hole formed in the plate 11c. Each of the first outflow passage 24a and the second outflow passage 24b is constituted by a through hole formed in the plate 11g. The nozzle 21 is located at a lower end portion of each of the individual passages 20 in the vertical direction (a one-side end portion of each of the individual passages 20 in the orthogonal direction).

Each of the supply liquid passages 31a, 31b is constituted by through holes formed in the respective plates 11c, 11d. Each of the return liquid passages 32a, 32b is constituted by through holes formed in the respective plates 11f, 11g.

Damper films 35a, 35b, 37a, 37b are provided respectively in the supply liquid passages 31a, 31b and the return liquid passages 32a, 32b. The damper films 35a, 35b define upper surfaces of the respective supply liquid passages 31a, 31b. The damper films 37a, 37b define lower surfaces of the respective return liquid passages 32a, 32b. Specifically, the plate 11b has: through holes respectively serving as damper chambers 34a, 34b at regions located over the respective supply liquid passages 31a, 31b. The damper films 35a, 35b are mounted on a lower surface of the plate 11b so as to cover the respective damper chambers 34a, 34b. The plate 11h has: through holes respectively serving as damper chambers 36a, 36b at regions located under the respective return liquid passages 32a, 32b. The damper films 37a, 37b are mounted on an upper surface of the plate 11h so as to cover the respective damper chambers 36a, 36b.

Each of the damper films 35a, 35b, 37a, 37b is a film-like member with a thickness that is less than that of each of the plates 11a-11i.

Here, there will be described the flow of ink in the liquid-passage defining plate 11. The arrows in FIGS. 2 and 4 indicate the flows of the ink.

As illustrated in FIG. 2, when the controller 5 drives a circulation pump 7p, the ink in the storage chamber 7a is supplied from the supply opening 41x to the supply coupling liquid passage 41. The ink supplied to the supply coupling liquid passage 41 flows in the supply coupling liquid passage 41 from the one side toward the other side in the arrangement direction and enters into the inlets 31ax, 31bx of the respective supply liquid passages 31a, 31b. The ink having flowed in the inlets 31ax of the respective first supply liquid passages 31a flows in the first supply liquid passages 31a from the one side toward the other side in the extending direction and enters into the first inlets 20a1 of the respective individual passages 20. The ink having flowed in the inlets 31bx of the respective second supply liquid passages 31b flows in the second supply liquid passages 31b from the one

side toward the other side in the extending direction and enters into the second inlets **20a2** of the respective individual passages **20**.

In each of the individual passages **20**, as illustrated in FIG. 4, the ink having flowed from the first supply liquid passage **31a** to the first inlet **20a1** enters into the pressure chamber **22** through the first inflow passage **23a**. In each of the individual passages **20**, the ink having flowed from the second supply liquid passage **31b** to the second inlet **20a2** enters into the pressure chamber **22** through the second inflow passage **23b**. A portion of the ink having entered into the pressure chamber **22** is ejected from the nozzle **21** while the remaining ink flows from the first outlet **20b1** to the first return liquid passage **32a** through the first outflow passage **24a** and from the second outlet **20b2** to the second return liquid passage **32b** through the second outflow passage **24b**.

As illustrated in FIG. 2, the ink having flowed in the first return liquid passage **32a** flows in the first return liquid passage **32a** from the one side toward the other side in the extending direction and enters from the outlet **32ax** into the return coupling liquid passage **51**. The ink having flowed in the second return liquid passage **32b** flows in the second return liquid passage **32b** from the one side toward the other side in the extending direction and enters from the outlet **32bx** into the return coupling liquid passage **51**. The ink having flowed in the return coupling liquid passage **51** flows in the return coupling liquid passage **51** from the other side toward the one side in the arrangement direction and enters from the return opening **51x** back into the storage chamber **7a**.

This circulation of the ink between the storage chamber **7a** and each of the individual passages **20** enables discharge of air bubbles from the individual passages **20** and prevents increase in viscosity of the ink. Furthermore, in the case where the ink contains settling components (components with a possibility of settling, such as pigments), the components are stirred, thereby preventing settling of the components.

The actuator unit **12** is disposed on an upper surface of the liquid-passage defining plate **11** so as to cover the pressure chambers **22**.

As illustrated in FIG. 4, the actuator unit **12** includes a vibration plate **12a**, a common electrode **12b**, a plurality of piezoelectric elements **12c**, and a plurality of individual electrodes **12d** stacked in order from below. The vibration plate **12a** and the common electrode **12b** cover the pressure chambers **22**. Each of the piezoelectric elements **12c** and each of the individual electrodes **12d** are provided for a corresponding one of the pressure chambers **22** so as to be opposed to the corresponding pressure chamber **22** in the orthogonal direction.

The individual electrodes **12d** and the common electrode **12b** are electrically connected to the driver IC **1d**. The driver IC **1d** keeps the electric potential of the common electrode **12b** at the ground potential and changes the electric potential of each of the individual electrodes **12d**. Specifically, the driver IC **1d** creates drive signals based on control signals output from the controller **5** and transmits the drive signals to the individual electrodes **12d**. As a result, the electric potential of each of the individual electrodes **12d** is changed between a predetermined driving potential and the ground potential. In this operation, for each of the piezoelectric elements **12c**, portions of the vibration plate **12a** and the piezoelectric element **12c** which are located between a corresponding one of the individual electrodes **12d** and a corresponding one of the pressure chambers **22** are deformed so as to protrude toward the pressure chamber **22**.

This changes the volume of the pressure chamber **22**, so that a pressure is applied to the ink in the pressure chamber **22** to eject the ink from a corresponding one of the nozzles **21**.

In the head **1** according to the present embodiment, as described above, two inlets (the first inlet **20a1** and the second inlet **20a2**) and two outlets (the first outlet **20b1** and the second outlet **20b2**) are provided for each of the individual passages **20** (see FIGS. 2-4). With this configuration, when compared with the case where one inlet and one outlet are formed for each of the individual passages **20**, it is difficult for the speed of ink flow to lower at the corner portions of each of the individual passages **20**, making it possible to reduce problems in which discharging of the air bubbles and stirring of the settling components are insufficient.

In the case where the supply liquid passages **31a**, **31b** and the return liquid passages **32a**, **32b** are arranged in a random configuration, the size of the entire liquid passages on the plane extending along the extending direction and the arrangement direction may increase. In the present embodiment, in contrast, the supply liquid passages **31a**, **31b** and the return liquid passages **32a**, **32b** extend in the same direction (the extending direction) and are arranged in the arrangement direction (see FIG. 2). The individual passages **20** are arranged in the extending direction in each row. This configuration reduces increase in size of the entire liquid passages on the above-described plane.

In the case where the first supply liquid passage **31a** and the second supply liquid passage **31b** are located on one side of the individual passages **20** in the arrangement direction, the first supply liquid passage **31a** and the second supply liquid passage **31b** need to be formed at positions different from each other in the orthogonal direction, which may increase the size of the head **1** in the orthogonal direction. In the present embodiment, in contrast, the first supply liquid passage **31a** and the second supply liquid passage **31b** are located on opposite sides of the individual passages **20** in the arrangement direction (see FIGS. 2 and 4). This configuration reduces the increase in size.

In the case where the first return liquid passage **32a** and the second return liquid passage **32b** are located on one side of the individual passages **20** in the arrangement direction, the first return liquid passage **32a** and the second return liquid passage **32b** need to be formed at positions different from each other in the orthogonal direction, which may increase the size of the head **1** in the orthogonal direction. In the present embodiment, in contrast, the first return liquid passage **32a** and the second return liquid passage **32b** are located on opposite sides of the individual passages **20** in the arrangement direction (see FIGS. 2 and 4). This configuration reduces the increase in size.

The first supply liquid passage **31a** and the first return liquid passage **32a** have a portion at which the first supply liquid passage **31a** and the first return liquid passage **32a** at least partly overlap each other in the orthogonal direction (see FIGS. 2 and 4). That is, the first supply liquid passage **31a** and the first return liquid passage **32a** are arranged so as to partly overlap each other when viewed in the orthogonal direction. This configuration reduces the size of a region for arrangement of the liquid passages in the arrangement direction, resulting in reduction in size of the head **1**.

The second supply liquid passage **31b** and the second return liquid passage **32b** have a portion at which the second supply liquid passage **31b** and the second return liquid passage **32b** at least partly overlap each other in the orthogonal direction (see FIGS. 2 and 4). That is, the second supply liquid passage **31b** and the second return liquid passage **32b**

are arranged so as to partly overlap each other when viewed in the orthogonal direction. This configuration reduces the size of a region for arrangement of the liquid passages in the arrangement direction, resulting in reduction in size of the head 1.

In the case where the first supply liquid passage 31a and the second supply liquid passage 31b are located at positions different from each other in the orthogonal direction, the flow of the ink supplied from the first supply liquid passage 31a to the individual passage 20 and the flow of the ink supplied from the second supply liquid passage 31b to the individual passage 20 are generated at positions different from each other in the orthogonal direction. In the case where the first return liquid passage 32a and the second return liquid passage 32b are located at positions different from each other in the orthogonal direction, the flow of the ink discharged from the individual passage 20 via the first return liquid passage 32a and the flow of the ink discharged from the individual passage 20 via the second return liquid passage 32b are generated at positions different from each other in the orthogonal direction. In the present embodiment, in contrast, the first supply liquid passage 31a and the second supply liquid passage 31b are located at the same position in the orthogonal direction (see FIG. 4). The first return liquid passage 32a and the second return liquid passage 32b are located at the same position in the orthogonal direction and are located respectively on the one side of the first supply liquid passage 31a and the second supply liquid passage 31b in the orthogonal direction. Thus, the flow of the ink supplied from the first supply liquid passage 31a to the individual passage 20 and the flow of the ink supplied from the second supply liquid passage 31b to the individual passage 20 are generated at the same position in the orthogonal direction, and the flow of the ink discharged from the individual passage 20 via the first return liquid passage 32a and the flow of the ink discharged from the individual passage 20 via the second return liquid passage 32b are generated at the same position in the orthogonal direction. Accordingly, the ink flows easily collide with each other in the individual passages 20, for example, making it possible to more effectively stir the settling components.

The nozzle 21 is located at the one-side end portion of each of the individual passages 20 in the orthogonal direction (see FIG. 4). Since each of the first return liquid passage 32a and the second return liquid passage 32b, and the nozzle 21 of each of the individual passages 20 are located on the same side (the lower side), it is easy to discharge air bubbles existing near the nozzle 21 from the individual passage 20 via the first return liquid passage 32a and the second return liquid passage 32b. The first supply liquid passage 31a and the second supply liquid passage 31b are located on an opposite side from the nozzle 21 of the individual passage 20. With this configuration, the ink supplied from the first supply liquid passage 31a and the second supply liquid passage 31b to the individual passage 20 smoothly flows toward the nozzle 21, causing ejection of the ink from the nozzle 21 with reduced driving force for the ejection.

The first supply liquid passage 31a, the second supply liquid passage 31b, the first return liquid passage 32a, and the second return liquid passage 32b are at least partly defined by the damper films 35a, 35b, 37a, 37b, respectively (see FIG. 4). With this configuration, the damper films 35a, 35b, 37a, 37b reduce fluid crosstalk between the individual passages 20.

In the case where a damper film provided for the first supply liquid passage 31a and the first return liquid passage 32a is located between the liquid passages 31a, 32a, it is

difficult to adjust a damping performance for each of the liquid passages 31a, 32a. Likewise, in the case where a damper film provided for the second supply liquid passage 31b and the second return liquid passage 32b is located between the liquid passages 31b, 32b, it is difficult to adjust a damping performance for each of the liquid passages 31b, 32b. In the present embodiment, in contrast, the damper films 35a, 35b provided respectively for the first supply liquid passage 31a and the second supply liquid passage 31b are located on the other side of the first supply liquid passage 31a and the second supply liquid passage 31b in the orthogonal direction (see FIG. 4). The damper films 37a, 37b provided respectively for the first return liquid passage 32a and the second return liquid passage 32b are located on the one side of the first return liquid passage 32a and the second return liquid passage 32b in the orthogonal direction. In the present embodiment as described above, the damper films are provided for the respective liquid passages 31a, 32a, 31b, 32b, making it easy to adjust the damping performance for each of the liquid passages 31a, 32a, 31b, 32b. The side surface of each of the liquid passages 31a, 32a, 31b, 32b has an opening continuing to a corresponding one of the inlets 20a1, 20a2 and the outlets 20b1, 20b2 of the individual passage, making it difficult to provide a damper film. In the present embodiment, however, the damper film is provided on the upper surface or the lower surface of each of the liquid passages 31a, 32a, 31b, 32b, making it easy to provide the damper film.

In each of the individual passages 20, the first inflow passage 23a and the second inflow passage 23b are arranged so as to be symmetric with respect to the center point O of the pressure chamber 22 on the plane extending along the extending direction and the arrangement direction (see FIG. 3). In this configuration, the ink flows collide with each other at the center point O of the pressure chamber 22, making it possible to more effectively stir the settling components in the entire pressure chamber 22.

In each of the individual passages 20, the first outflow passage 24a and the second outflow passage 24b are arranged so as to be symmetric with respect to the center point O and so as not to overlap the first inflow passage 23a and the second inflow passage 23b in the orthogonal direction (see FIG. 3). That is, the first outflow passage 24a and the second outflow passage 24b are arranged so as to be symmetric with respect to the center point O and so as not to overlap the first inflow passage 23a and the second inflow passage 23b when viewed in the orthogonal direction. With this configuration, the flow of the ink from the center point O toward each of the outlets 20b1, 20b2 is generated at the center point O of the pressure chamber 22, making it possible to more effectively stir the settling components.

The first outflow passage 24a and the second outflow passage 24b are located on the one side of the first inflow passage 23a and the second inflow passage 23b in the orthogonal direction (see FIG. 4). That is, each of the first outflow passage 24a and the second outflow passage 24b, and the nozzle 21 of each of the individual passages 20 are located on the same side. This configuration makes it easy to discharge air bubbles existing near the nozzle 21, from the individual passage 20 via the first outflow passage 24a or the second outflow passage 24b.

The first inflow passage 23a, the second inflow passage 23b, the first outflow passage 24a, and the second outflow passage 24b are connected to the respective corner portions c1-c4 of the pressure chamber 22 (see FIG. 3). The corner portions c1-c4 of the pressure chamber 22 are regions in which the speed of ink flow easily lowers in particular, and

11

air bubbles easily remain. In the present embodiment, since the inflow passages 23a, 23b and the outflow passages 24a, 24b are connected to the respective corner portions c1-c4, the flow of the ink is easily generated at the corner portions c1-c4, making it difficult for the air bubbles to remain.

Second Embodiment

There will be next described a head 201 according to a second embodiment with reference to FIG. 6. The present embodiment is different from the first embodiment in configuration of damper films provided for the supply liquid passages 31a, 31b and the return liquid passages 32a, 32b.

In the first embodiment, the damper films 35a, 35b are provided on the upper surfaces of the respective supply liquid passages 31a, 31b, and the damper films 37a, 37b are provided on the lower surfaces of the respective return liquid passages 32a, 32b (see FIG. 4).

In the present embodiment, a single damper film 235 contacting the first supply liquid passage 31a and the first return liquid passage 32a is provided between the first supply liquid passage 31a and the first return liquid passage 32a in the orthogonal direction. The damper film 235 defines the lower surface of the first supply liquid passage 31a and the upper surface of the first return liquid passage 32a. A single damper film 237 contacting the second supply liquid passage 31b and the second return liquid passage 32b is provided between the second supply liquid passage 31b and the second return liquid passage 32b in the orthogonal direction. The damper film 237 defines the lower surface of the second supply liquid passage 31b and the upper surface of the second return liquid passage 32b. Specifically, the damper films 235, 237 are provided on the lower surface of the plate 11e so as to cover through holes 234, 236 formed in the plate 11e.

In the present embodiment, the damper film 235 cancels out pressure waves between the first supply liquid passage 31a and the first return liquid passage 32a, and the damper film 237 cancels out pressure waves between the second supply liquid passage 31b and the second return liquid passage 32b.

Third Embodiment

There will be next described a head 301 according to a third embodiment with reference to FIG. 7. The present embodiment is different from the first embodiment in configuration of damper films provided for the supply liquid passages 31a, 31b and the return liquid passages 32a, 32b.

In the first embodiment, the damper films 35a, 35b are provided on the upper surfaces of the respective supply liquid passages 31a, 31b, and the damper films 37a, 37b are provided on the lower surfaces of the respective return liquid passages 32a, 32b (see FIG. 4).

In the present embodiment, two damper films 335a, 335b spaced apart from each other in the orthogonal direction are provided between the first supply liquid passage 31a and the first return liquid passage 32a in the orthogonal direction. Two damper films 337a, 337b spaced apart from each other in the orthogonal direction are provided between the second supply liquid passage 31b and the second return liquid passage 32b in the orthogonal direction. The damper films 335a, 337a are provided on the upper surface of the plate 11e so as to respectively cover through holes 334, 336 formed in the plate 11e. The damper films 335b, 337b are provided on the lower surface of the plate 11e so as to respectively cover the through holes 334, 336.

12

In the present embodiment, a space between the damper films 335a, 335b and a space between the damper films 337a, 337b achieve the effects of damping the pressure waves.

5

Fourth Embodiment

There will be next described a head 401 according to a fourth embodiment with reference to FIGS. 8 and 9. The present embodiment is different from the first embodiment in configuration of the inflow passages and the outflow passages of each of the individual passages.

In the first embodiment, in each of the individual passages 20, the first inflow passage 23a and the second inflow passage 23b are arranged so as to be symmetric with respect to the center point O of the pressure chamber 22, and the first outflow passage 24a and the second outflow passage 24b are arranged so as to be symmetric with respect to the center point O of the pressure chamber 22 on the plane extending along the extending direction and the arrangement direction (see FIG. 3).

In the present embodiment, in each of individual passages 420, a first inflow passage 423a and a second inflow passage 423b are arranged so as to be symmetric with respect to the axis A extending along the extending direction through the center of the pressure chamber 22 in the arrangement direction, and a first outflow passage 424a and a second outflow passage 424b are arranged so as to be symmetric with respect to the axis A.

In the present embodiment, the first inflow passage 423a and the second inflow passage 423b are arranged so as to be symmetric with respect to the axis A. The ink flows collide with each other at a portion of the pressure chamber 22 which is located on the axis A (i.e., a portion of the pressure chamber 22 at which the first inflow passage 423a and the second inflow passage 423b are opposed to each other in the arrangement direction), making it possible to more effectively stir the settling components in the entire pressure chamber 22.

The first outflow passage 424a and the second outflow passage 424b are arranged so as to be symmetric with respect to the axis A. The ink flows collide with each other at a portion of the pressure chamber 22 which is located on the axis A (i.e., a portion of the pressure chamber 22 at which the first outflow passage 424a and the second outflow passage 424b are opposed to each other in the arrangement direction), making it possible to more effectively stir the settling components in the entire pressure chamber 22. The flow of the ink from the portion of the pressure chamber 22 which is located on the axis A (i.e., a portion of the pressure chamber 22 at which the first outflow passage 424a and the second outflow passage 424b are opposed to each other in the arrangement direction), toward each of the outlets 20b1, 20b2 is generated at the portion of the pressure chamber 22 which is located on the axis A, making it possible to much more effectively stir the settling components.

Fifth Embodiment

There will be next described a head according to a fifth embodiment with reference to FIG. 10. The present embodiment is different from the first embodiment in configuration of the inflow passages of each of the individual passages.

In the first embodiment, in each of the individual passages 20, the first inflow passage 23a and the second inflow passage 23b are connected to the respective sides s1, s2 of the pressure chamber 22 which extend in the extending

direction (see FIG. 3). The first inflow passage 23a and the first outflow passage 24a are connected to the side s1, and the second inflow passage 23b and the second outflow passage 24b are connected to the side s2. No inflow passages and outflow passages are connected to the sides s3, s4 extending in the arrangement direction.

In the present embodiment, in each of individual passages 520, a first inflow passage 523a and a second inflow passage 523b are connected to the respective sides s3, s4 of the pressure chamber 22 which extend in the arrangement direction. Each of the first inflow passage 523a and the second inflow passage 523b is bent or curved on the plane extending along the extending direction and the arrangement direction. The first outflow passage 24a is connected to the side s1, the second outflow passage 24b to the side s2, the first inflow passage 523a to the side s3, and the second inflow passage 523b to the side s4.

In the present embodiment, the first outflow passage 24a, the second outflow passage 24b, the first inflow passage 523a, and the second inflow passage 523b are connected respectively to the different sides s1-s4 of the pressure chamber 22. Thus, the ink flows in various directions in the pressure chamber 22, making it possible to much more effectively stir the settling components.

Modifications

While the embodiments have been described above, it is to be understood that the disclosure is not limited to the details of the illustrated embodiments, but may be embodied with various changes and modifications, which may occur to those skilled in the art, without departing from the spirit and scope of the disclosure.

While two inlets and two outlets formed in each of the individual passages in the above-described embodiments, three or more inlets and/or three or more outlets may be formed. In this case, three or more supply liquid passages and/or three or more return liquid passages may be connected to each of the individual passages.

While a plurality of the first supply liquid passages, a plurality of the second supply liquid passages, a plurality of the first return liquid passages, and a plurality of the second return liquid passages are formed in the above-described embodiments, the single first supply liquid passage, the single second supply liquid passage, the single first return liquid passage, and single the second return liquid passage may be formed.

The first supply liquid passages, the second supply liquid passages, the first return liquid passages, and the second return liquid passages extend in the same direction in the above-described embodiments and may extend in different directions.

In the above-described embodiment (FIGS. 2 and 4), the first supply liquid passage 31a and the first return liquid passage 32a coincide with each other in the orthogonal direction substantially entirely on the plane orthogonal to the orthogonal direction, but the present disclosure is not limited to this configuration. That is, the first supply liquid passage and the first return liquid passage only have to at least partly overlap each other in the orthogonal direction. Thus, the first supply liquid passage and the first return liquid passage may be slightly different from each other in position in the extending direction, for example. Likewise, in the above-described embodiment (FIGS. 2 and 4), the second supply liquid passage 31b and the second return liquid passage 32b coincide with each other in the orthogonal direction substantially entirely on the plane orthogonal to the orthogonal direction, but the present disclosure is not limited to this configuration. That is, the second supply liquid passage and

the second return liquid passage only have to at least partly overlap each other in the orthogonal direction. Thus, the second supply liquid passage and the second return liquid passage may be slightly different from each other in position in the extending direction, for example.

The first supply liquid passage and the second supply liquid passage may be located on one side of the individual passages in the arrangement direction. Likewise, the first return liquid passage and the second return liquid passage may be located on one side of the individual passages in the arrangement direction.

The positions of the supply coupling liquid passage and the return coupling liquid passage are not limited in particular. For example, the supply coupling liquid passage and the return coupling liquid passage may be located on one side of the first supply liquid passages, the second supply liquid passages, the first return liquid passages, and the second return liquid passages in the extending direction and may overlap each other in the orthogonal direction. It is noted that the first supply liquid passages and the second supply liquid passages may not be coupled to each other by the supply coupling liquid passage and may be connected to the storage chamber individually. Likewise, the first return liquid passage and the second return liquid passage may not be coupled to each other by the return coupling liquid passage and may be connected to the storage chamber individually.

In each of the first supply liquid passages, the second supply liquid passages, the first return liquid passages, and the second return liquid passages, a damper film may be provided on a side surface of the liquid passage which has an opening continuing to the inlet or the outlet of the individual passage. No damper film may be provided for each of the first supply liquid passages, the second supply liquid passages, the first return liquid passages, and the second return liquid passages.

The positional relationship among the first supply liquid passages, the second supply liquid passages, the first return liquid passages, and the second return liquid passages in the orthogonal direction is not limited in particular. For example, the first supply liquid passage and the second supply liquid passage may be located at different positions in the orthogonal direction. The first return liquid passage and the second return liquid passage may be located at different positions in the orthogonal direction. The first supply liquid passage and the second supply liquid passage may be located below the first return liquid passage and the second return liquid passage. In other words, the first supply liquid passage and the second supply liquid passage may be located on the one side of the first return liquid passage and the second return liquid passage in the orthogonal direction.

In the above-described embodiment (FIG. 2), the pair of the first supply liquid passage 31a and the first return liquid passage 32a or the pair of the second supply liquid passage 31b and the second return liquid passage 32b formed between two of the rows of the individual passages 20 which are adjacent to each other in the arrangement direction communicate with the individual passages 20 belonging to the two rows. However, the present disclosure is not limited to this configuration. For example, the pair of the first supply liquid passage 31a and the first return liquid passage 32a and the pair of the second supply liquid passage 31b and the second return liquid passage 32b may be formed for each row of the individual passages 20.

The individual passages need not be arranged in rows and may be arranged on a random basis.

15

The configuration of each of the individual passages (e.g., the shape of the pressure chamber and a manner of communication between the pressure chamber and the nozzle) is not limited in particular. For example, the pressure chamber may have any shape on the plane extending along the extending direction and the arrangement direction, such as a square, a parallelogram, a rhombus, a perfect circle, and an oval. While the pressure chamber is formed just above the nozzle in the above-described embodiments, the present disclosure is not limited to this configuration. For example, another liquid passage establishing communication between the pressure chamber and the nozzle may be formed. Each of the number of the nozzles and the number of the pressure chambers in each of the individual passages is not limited to one and may be two or more.

The positions of the first inflow passage, the second inflow passage, the first outflow passage, and the second outflow passage are not limited in particular. For example, the head may be configured such that the first outflow passage 24a and the second outflow passage 24b do not overlap the first inflow passage 23a and the second inflow passage 23b in the orthogonal direction in the above-described embodiment (FIG. 3) but may overlap the first inflow passage 23a and the second inflow passage 23b in the orthogonal direction, respectively. The head may be configured such that the first inflow passage 23a and the first outflow passage 24a overlapping each other in the orthogonal direction are connected to the center of the side s1 in the extending direction, and the second inflow passage 23b and the second outflow passage 24b overlapping each other in the orthogonal direction are connected to the center of the side s2 in the extending direction. That is, each of the first inflow passage, the second inflow passage, the first outflow passage, and the second outflow passage need not be connected to a corresponding one of the corner portions of the pressure chamber. The first inflow passage, the second inflow passage, the first outflow passage, and the second outflow passage may be located at the same position in the orthogonal direction. The first inflow passage and the second inflow passage may be located below the first outflow passage and the second outflow passage, in other words, the first inflow passage and the second inflow passage may be located on the one side of the first outflow passage and the second outflow passage in the orthogonal direction.

The actuator is not limited to the piezoelectric actuator using piezoelectric elements and may be of any other type such as a thermal actuator using heating elements and an electrostatic actuator using an electrostatic force.

The head is not limited to the line head and may be a serial head which ejects liquid from nozzles onto a recording medium while moving in a scanning direction parallel with the widthwise direction of the sheet.

The recording medium is not limited to the sheet and may be any of a cloth, a circuit board, and the like.

The liquid ejected from the nozzles is not limited to the ink and may be any other type of liquid such as treatment liquid that coagulates or precipitates components of the ink.

The present disclosure is applied to the printer in the above-described embodiments but may be applied to a facsimile, a copying machine, and a multi-function peripheral (MFP), for example. The present disclosure may also be applied to a liquid ejection apparatus used for purposes different from image recording. For example, the present disclosure may be applied to a liquid ejection apparatus configured to eject conductive liquid onto a substrate to form a conductive pattern on the substrate.

16

What is claimed is:

1. A liquid ejection head, comprising:
a plurality of individual passages each comprising a nozzle;
a first supply liquid passage communicating with a first inlet of each of the plurality of individual passages;
a second supply liquid passage communicating with a second inlet of each of the plurality of individual passages;
a first return liquid passage communicating with a first outlet of each of the plurality of individual passages; and
a second return liquid passage communicating with a second outlet of each of the plurality of individual passages.
2. The liquid ejection head according to claim 1, wherein the first supply liquid passage, the second supply liquid passage, the first return liquid passage, and the second return liquid passage extend in an extending direction and are arranged in an arrangement direction intersecting the extending direction, and wherein the plurality of individual passages are arranged in the extending direction.
3. The liquid ejection head according to claim 2, wherein the first supply liquid passage and the second supply liquid passage are located respectively on opposite sides of the plurality of individual passages in the arrangement direction.
4. The liquid ejection head according to claim 3, wherein the first supply liquid passage and the first return liquid passage are arranged so as to at least partly overlap each other when viewed in an orthogonal direction orthogonal to each of the extending direction and the arrangement direction.
5. The liquid ejection head according to claim 4, wherein the second supply liquid passage and the second return liquid passage are arranged so as to at least partly overlap each other when viewed in the orthogonal direction.
6. The liquid ejection head according to claim 5, wherein the first supply liquid passage and the second supply liquid passage are located at an identical position in the orthogonal direction, and wherein the first return liquid passage and the second return liquid passage are located at an identical position in the orthogonal direction and located on one side of the first supply liquid passage and the second supply liquid passage in the orthogonal direction.
7. The liquid ejection head according to claim 6, wherein the nozzle is located at one of opposite end portions of each of the plurality of individual passages in the orthogonal direction, which one is located on the one side of the other of the opposite end portions in the orthogonal direction.
8. The liquid ejection head according to claim 6, wherein at least a portion of each of the first supply liquid passage, the second supply liquid passage, the first return liquid passage, and the second return liquid passage is defined by a damper film.
9. The liquid ejection head according to claim 8, wherein the damper film provided for each of the first supply liquid passage and the second supply liquid passage is located on the other side of the first supply liquid passage and the second supply liquid passage in the orthogonal direction, and wherein the damper film provided for each of the first return liquid passage and the second return liquid passage is located on the one side of the first return liquid passage and the second return liquid passage in the orthogonal direction.

17

10. The liquid ejection head according to claim 8, wherein a single damper film as the damper film which contacts the first supply liquid passage and the first return liquid passage is provided between the first supply liquid passage and the first return liquid passage in the orthogonal direction, and wherein a single damper film as the damper film which contacts the second supply liquid passage and the second return liquid passage is provided between the second supply liquid passage and the second return liquid passage in the orthogonal direction. 10

11. The liquid ejection head according to claim 8, wherein two damper films each as the damper film which are spaced apart from each other in the orthogonal direction are provided between the first supply liquid passage and the first return liquid passage in the orthogonal direction, and wherein two damper films each as the damper film which are spaced apart from each other in the orthogonal direction are provided between the second supply liquid passage and the second return liquid passage in the orthogonal direction. 20

12. The liquid ejection head according to claim 2, wherein the first return liquid passage and the second return liquid passage are located respectively on opposite sides of the plurality of individual passages in the arrangement direction. 25

13. The liquid ejection head according to claim 3, wherein each of the plurality of individual passages comprises:
a pressure chamber communicating with the nozzle;
a first inflow passage connecting the pressure chamber and the first inlet to each other; and
a second inflow passage connecting the pressure chamber and the second inlet to each other, and wherein, in each of the plurality of individual passages, the first inflow passage and the second inflow passage are arranged so as to be symmetric with respect to a center point of the pressure chamber on a plane extending along the extending direction and the arrangement direction when viewed in an orthogonal direction 35 orthogonal to each of the extending direction and the arrangement direction. 40

14. The liquid ejection head according to claim 13, wherein each of the plurality of individual passages comprises:
a pressure chamber communicating with the nozzle;
a first outflow passage connecting the pressure chamber and the first outlet to each other; and
a second outflow passage connecting the pressure chamber and the second outlet to each other, and wherein, in each of the plurality of individual passages, the first outflow passage and the second outflow passage are arranged so as to be symmetric with respect to a center point of the pressure chamber on a plane extending along the extending direction and the arrangement direction when viewed in the orthogonal direction and are arranged so as not to overlap the first inflow passage and the second inflow passage when viewed in the orthogonal direction. 50 55

15. The liquid ejection head according to claim 3, wherein each of the plurality of individual passages comprises:
a pressure chamber communicating with the nozzle;
a first inflow passage connecting the pressure chamber and the first inlet to each other; and
a second inflow passage connecting the pressure chamber and the second inlet to each other, and 60 65

18

wherein, in each of the plurality of individual passages, the first inflow passage and the second inflow passage are arranged so as to be symmetric with respect to an axis extending along the extending direction through a center of the pressure chamber in the arrangement direction when viewed in an orthogonal direction orthogonal to each of the extending direction and the arrangement direction.

16. The liquid ejection head according to claim 3, wherein each of the plurality of individual passages comprises:
a pressure chamber communicating with the nozzle;
a first outflow passage connecting the pressure chamber and the first outlet to each other; and
a second outflow passage connecting the pressure chamber and the second outlet to each other, and wherein, in each of the plurality of individual passages, the first outflow passage and the second outflow passage are arranged so as to be symmetric with respect to an axis extending along the extending direction through a center of the pressure chamber in the arrangement direction when viewed in an orthogonal direction orthogonal to each of the extending direction and the arrangement direction.

17. The liquid ejection head according to claim 2, wherein each of the plurality of individual passages comprises:
a pressure chamber communicating with the nozzle;
a first inflow passage connecting the pressure chamber and the first inlet to each other;
a second inflow passage connecting the pressure chamber and the second inlet to each other;
a first outflow passage connecting the pressure chamber and the first outlet to each other; and
a second outflow passage connecting the pressure chamber and the second outlet to each other, and wherein, in each of the plurality of individual passages, the nozzle is located on one side of the pressure chamber in an orthogonal direction orthogonal to each of the extending direction and the arrangement direction, and the first outflow passage and the second outflow passage are located on the one side of the first inflow passage and the second inflow passage in the orthogonal direction.

18. The liquid ejection head according to claim 2, wherein each of the plurality of individual passages comprises:
a pressure chamber communicating with the nozzle;
a first inflow passage connecting the pressure chamber and the first inlet to each other;
a second inflow passage connecting the pressure chamber and the second inlet to each other;
a first outflow passage connecting the pressure chamber and the first outlet to each other; and
a second outflow passage connecting the pressure chamber and the second outlet to each other, and wherein, in each of the plurality of individual passages, the pressure chamber comprises at least four corner portions on a plane extending along the extending direction and the arrangement direction, and the first inflow passage, the second inflow passage, the first outflow passage, and the second outflow passage are respectively connected to four of the at least four corner portions which are different from each other.

19. The liquid ejection head according to claim 2, wherein each of the plurality of individual passages comprises:

a pressure chamber communicating with the nozzle;
a first inflow passage connecting the pressure chamber
and the first inlet to each other;
a second inflow passage connecting the pressure chamber
and the second inlet to each other; 5
a first outflow passage connecting the pressure chamber
and the first outlet to each other; and
a second outflow passage connecting the pressure chamber
and the second outlet to each other, and
wherein, in each of the plurality of individual passages, 10
the pressure chamber comprises at least four sides on a plane extending along the extending direction and the arrangement direction, and the first inflow passage, the second inflow passage, the first outflow passage, and the second outflow passage are respectively connected 15
to four of the at least four sides which are different from each other.
